UNITED STATES' PATENT OFFICE.

AUGUSTUS F. W. MACMANUS, OF SAN ANTONIO, TEXAS, ASSIGNOR OF ONE-TENTH TO
J. E. GREER AND J. B. STAFFORD, BOTH OF SAN ANTONIO, TEXAS.

MEDICINAL APPARATUS.

1,424,111.

Specification of Letters Patent. Patented July 25, 1922.

Application filed January 8, 1921. Serial No. 425,847.

To all whom it may concern:

Be it known that I, AUGUSTUS F. W. MACMANUS, a citizen of the United States, residing at San Antonio, in the county of Bexar and State of Texas, have invented certain new and useful Improvements in Medicinal Apparatus, of which the following is a specification.

This invention relates to medicinal apparatus, and it comprises a chamber for burning wood or other suitable material, an outlet for the products of combustion, a settling chamber for a portion of the products of combustion, said chamber being provided with means for removing carbon or other solid impurities from the gases, a conditioning chamber arranged adjacent said settling chamber, a perforated plate separating said chambers, said conditioning chamber being adapted to contain earth, or other material for treating the gases, and an outlet chamber connected to said conditioning chamber.

In the present invention, I have provided apparatus for use in treating tuberculosis, and similar diseases, wherein vapors or fumes are to be inhaled by the patient or patients, for the ailment referred to. Any suitable hard wood, or other material, such as oak, hickory, or other woods producing fumes containing creosote, phenols, and similar materials, which are desirable for such treatment may be burned in a fire chamber or fire box.

The products of combustion passing from the fire box contain carbon and other solid impurities which are detrimental in the treatment, and which should be removed from the vapors or gases being inhaled by the patients.

In the present invention, I provide a settling chamber for the purpose of removing carbon and other solid impurities. The products of combustion or a portion thereof, pass into this chamber which is provided with a plurality of baffle plates or other similar means to retard the flow of gases, and cause deposition of carbon and other solid impurities by gravity. From the settling chamber, the partly clarified and purified gases and vapors containing the volatile constituents of the wood or other material, are delivered to a conditioning chamber which may contain earth, earthy

material, clay or any other suitable material for removing final traces of solid impurities and properly conditioning the vapors and gases for use.

In one form of the invention, I provide a sectional apparatus suitable for use in sanitariums, hospitals, and similar places wherein the capacity may be adjusted to suit the particular conditions of any given place. In another form of the invention, I provide a similar apparatus suitable for use in the homes of the patients.

In the accompanying drawings, I have shown several embodiments of the invention. In this showing:

Figure 1 is a perspective view of one form of the apparatus showing several units arranged in series,

Figure 2 is a vertical transverse sectional view through the settling chamber and conditioning chamber,

Figure 3 is a detail perspective view of a series of baffle plates,

Figure 4 is a vertical longitudinal sectional view of several units,

Figure 5 is a detail view of the grate employed in the fire box,

Figure 6 is a similar view of the perforated baffle plate arranged between the settling chamber and the conditioning chamber,

Figure 7 is a front elevation of another form of the invention,

Figure 8 is a detail view of the grate employed therein,

Figure 9 is a horizontal sectional view of the form shown in Figure 7,

Figure 10 is a detail perspective view of one of the baffle plates,

Figure 11 is a vertical sectional view, and,

Figure 12 is a detail view of the outlet pipe.

Referring to Figures 1 to 6 of the drawings, the reference numeral 1 designates, generally, a casing which may be made of any suitable shape and size, and which is adapted to be supported on legs 2. The ends of the casing are provided with flanges 3 for the reception of bolts adapted to pass through end plates 4, whereby the end plates may be readily attached and removed. When a single unit is being employed, an end plate is arranged at each end of the apparatus to close it, and when a plurality

of units are being used in series, as shown in Figures 1 to 4 of the drawings, the adjacent ends are brought together and the bolts pass through the openings which are adapted to register with each other (see Figure 4).

At one end of the casing, a fire box 5 is provided, separated from the remainder of the casing by a vertical wall 6. The fire box 10 may be provided with any suitable type of door 7. A grate 8, which as shown, consists of a perforated plate, is arranged within the fire box and is supported and spaced from the bottom of the casing by means of 15 legs 9, formed by extending the ends of the cross plates 10 downwardly. The fire box is provided with an outlet opening 11 communicating with a main pipe or stack 12, through which the majority of the products 20 of combustion are passed to a suitable source of disposal. The fire box is connected to the stack or pipe 12 by a branch pipe 13, which may be provided with a damper 14, whereby the proportion of the products of 25 combustion passed to waste may be regulated.

A settling chamber 15 is arranged adjacent the fire box, and separated therefrom by the vertical wall 6. As shown, the vertical wall terminates below the top of the casing forming a passage 16 to permit communication between the fire box and the settling chamber. The upper end of the wall is provided with a substantially horizontal portion 17, the terminal of which is extended downwardly, as at 18. Suitable openings 19 may be arranged in the horizontal portion 17, and similar openings 20, preferably of a large size, may be arranged in the rear 30 wall 6. A plate 21 is supported from the top of the casing, spaced from the wall 6, and extending downwardly below the passage 16. This plate is provided with a horizontal portion 22, and a vertical portion 23. 40 It may be further provided with a series of openings 24, arranged substantially in alignment with the passage 16. A plate 25, similar to the rear wall of the furnace is supported on the bottom of the settling chamber 45 and suitably spaced from the plate 21. As shown, this plate is provided with a substantially horizontal portion 26, a downwardly extending end 27, and is further provided with openings 28 and 29, similar in 50 size and arrangement to the openings 19 and 20. A second plate 21 is arranged beyond the plate 25. A conditioning chamber 30 is arranged above the settling chamber and separated therefrom by a plate 31. As 55 shown, the plate 31 is provided with a series of lips 32, forming openings permitting communication between the settling chamber and the conditioning chamber. The plate 31 is adapted to support the earth, 60 clay, or other material used for conditioning 65

the fumes and vapors passing from the settling chamber to the conditioning chamber. The settling chamber may be closed by any suitable type of cover 33, and is provided with a vapor outlet 34. When several units 70 of the apparatus are employed in series, the fire box may be provided with walls on each side, as illustrated in dotted lines in Figure 4 of the drawings.

In the form of the invention shown in 75 Figures 7 to 12 of the drawings, there is provided a substantially cylindrical casing 35 having a grate 36, arranged in the bottom thereof and supported on legs 37. The fire box is provided with a door 38 of any suitable construction. A portion of the products of combustion pass from the fire box through an outlet pipe or stack 39 which may be provided with any suitable type of chamber 40.

A plurality of horizontally arranged baffle plates 41 are disposed above the grate and form the settling chamber. These baffle plates are alternately arranged, being secured to the wall of the casing and extending to a point beyond the middle. They are provided with downwardly extending portions 42 having openings 43. The ends of the baffle plates are extended in a substantially horizontal plane, as at 44, and spaced 95 from the body portion 41. The conditioning chamber is separated from the settling chamber by means of a perforated plate 45, adapted to receive and support the material with which the vapors are to be treated. 100 The settling chamber is provided with a closed top 46 and an outlet 47.

In the use of the apparatus, any suitable hard wood, such as hickory, oak, or any other material capable of producing creosote vapors, phenol vapors, or other material desirable for use in the treatment of tuberculosis, catarrh, and diseases of like nature are placed in the fire box 5 and burned. The combustion is controlled to prevent decomposition of the volatile constituents of the wood or other material. A portion of the products of combustion, if not needed, may be exhausted through outlet 11, and stack 12, and a portion thereof delivered to the 110 settling chamber. The proportion of the products of combustion delivered to the settling chamber may be regulated by damper 14. The products of combustion pass through the settling chamber in a zig-zag 115 path, retarding the passage of the gases, and the flow of the gases is further retarded by means of the horizontal portions formed on the ends of the baffle plates and the spaced vertical portions. A portion of the products 120 of combustion will pass through the openings 19, 20, 24, 28 and 29. While passing through the settling chamber, the solid impurities which are detrimental in the treatment are removed by gravity, and the gases 125 130

and vapors are delivered to the conditioning chamber 30. The gases and vapors from which the solid particles have been substantially removed are delivered to the conditioning chamber 30 through the opening 5 in the perforated plate 31. The earth, clay, or other material, in the conditioning chamber is preferably disintegrated to permit the gases and vapors to percolate through it, and 10 remove the final traces of carbon or other undesirable heavier elements. The earth or clay may be moistened with water, or with certain chemicals such as a solution of permanganate of potash, or other material 15 which may be artificially added to the earth or clay.

In the form of the apparatus shown in Figures 7 to 12 of the drawings, the operation is essentially the same. This type of 20 apparatus is primarily intended for domestic use where a small number of patients are to be treated. In the form of the apparatus shown in Figures 1 to 6 of the drawings, the 25 sectional construction permits the use of any desired number of units, whereby the apparatus may be assembled according to the size of the particular room or building in which it is employed. This type of apparatus is adapted for use in sanitariums, hospitals, 30 and similar places where a large number of patients are to be treated.

In the other form of the apparatus, a portable construction is employed which may be readily moved from place to place 35 and installed and operated.

It is to be understood that the forms of my invention herewith shown and described are to be taken as preferred examples of the same, and that various changes in the shape, 40 size, and arrangement of parts may be resorted to without departing from the spirit of the invention or the scope of the subjoined claims.

Having thus described my invention, I 45 claim:

1. A medicinal apparatus comprising a fire box, a settling chamber arranged adjacent said fire box, a plurality of baffle plates arranged therein, and a conditioning chamber 50 arranged adjacent said settling chamber and communicating therewith.

2. A medicinal apparatus comprising a fire box, a settling chamber arranged adjacent said fire box, a plurality of baffle plates 55 arranged therein, said baffle plates being provided with flanged ends to retard the passage of gases, and a conditioning chamber arranged adjacent said settling chamber and communicating therewith.

60 3. A medicinal apparatus comprising a casing, said casing being provided with flanged ends, an end plate adapted to be arranged thereon, the flanged ends of the casing being adapted to be secured to a second 65 casing to permit the use of a plurality of

units in a single apparatus, a fire box arranged in said casing, and means for separating the solid impurities produced in burning wood from the lighter volatile constituents.

4. A medicinal apparatus comprising a casing, a fire box arranged adjacent one end of said casing, a settling chamber arranged adjacent said fire box, a plurality of baffle plates arranged therein, said plates being alternately secured to the top and bottom of the casing to produce a tortuous passage, and a conditioning chamber arranged adjacent said settling chamber and communicating therewith. 70

5. A medicinal apparatus comprising a casing, a fire box arranged adjacent one end of said casing, a settling chamber arranged adjacent said fire box, a plurality of baffle plates arranged therein, said plates being alternately secured to the top and bottom of the casing, the inner ends of said plates being provided with off-set portions arranged at substantially right angles to the body portion of the plate, and a conditioning chamber 85 arranged adjacent said settling chamber and communicating therewith. 90

6. A medicinal apparatus, comprising a casing, a fire box arranged adjacent one end of said casing, a settling chamber arranged 95 adjacent said fire box, a plurality of baffle plates arranged therein, alternate plates being secured to the top and bottom of the casing to form a tortuous passage for the gases produced in the fire box, the inner ends of 100 said plates being provided with off-sets forming pockets, said plates being provided with spaced openings, and a conditioning chamber arranged adjacent said settling chamber and communicating therewith. 105

7. A medicinal apparatus, comprising a casing, a fire box arranged therein, said fire box being provided with an outlet opening for disposal of a portion of the products of combustion, a settling chamber adjacent said 110 fire box and adapted to receive a portion of the products of combustion, means for regulating the portion of the products of combustion passing through said outlet, means for retarding the flow of gases through said settling chamber to remove solid impurities, and a conditioning chamber arranged adjacent 115 said settling chamber and communicating therewith.

8. A medicinal apparatus, comprising a 120 casing, a fire box arranged adjacent one end of said casing, a settling chamber arranged adjacent said fire box and communicating therewith, a plurality of baffle plates arranged therein, a conditioning chamber arranged above said settling chamber, said chambers being separated by a perforated wall to permit passage of gases from the settling chamber to the conditioning chamber, and to support the material used to 125 130

- treat the gases in the conditioning chamber, and an outlet in said conditioning chamber for the treated gases.
9. An apparatus for generating medicinal fumes comprising a casing, a fire box arranged therein, said fire box being provided with an outlet opening for disposal of a portion of the products of combustion, a conditioning chamber in communication with said fire box and through which passes the remaining products of combustion and filter-

ing material in said conditioning chamber adapted to remove solid particles from the products of combustion passing therethrough.

In testimony whereof I affix my signature in presence of two witnesses.

AUGUSTUS F. W. MACMANUS.
